COCKTAIL GLASS OR SIMILAR ARTICLE

Victor J. Bergeron, Orinda, Calif.

Application July 9, 1958, Serial No. 51,712

Term of patent 14 years

(Cl. D36—8)

Fig. 1 is a front view of a cocktail glass or similar article in which the dominant feature is the stem, the conventional base and bowl portion being shown in dotted lines.

Fig. 2 is a side view of the stem of the cocktail glass or similar article the bowl and base omitted for convenience of illustration.

I claim:

An ornamental design for a cocktail glass or similar article, as shown and described.
